GAS FURNACE

Heinz Becker, Hamburg, Germany

Application March 31, 1939, Serial No. 265,320
In Germany March 31, 1938

6 Claims. (Cl. 158—99)

This invention relates to a gas furnace for smoke producing devices, curing apparatus, etc.

In a known gas furnace of this class the burner tube for the furnace is provided with gas outlet openings, arranged at a distance above a grate receiving the smoke producing material and covered with a protective cap which is movable arranged on a rotatable shaft to permit its removal from the burner tube if required.

10 This known gas furnace is open to the objection that it comprises a plurality of independent parts whereby its installation is rendered difficult.

It is the object of the invention to overcome this drawback and to provide a gas furnace for 15 smoke producing devices, curing apparatus, etc., which owing to the omission of loose or mechanically movable parts is of simplified construction so that the furnace can be readily installed or removed.

20 The invention attains its object by combining the burner tube and the protective cap arranged above it into a unitary structure in the base portion of which perforations for the supply of air are provided, the entire structure resembling a 25 grate bar.

In further accordance with the invention the burner tube is positioned between the grate bars which receive the smoke producing fuel and is on a level with the lower edge of these bars.

30 One form of the invention is illustrated in the accompanying drawing, in which—

Figure 1 is a cross section of those portions of a gas furnace with which the invention is concerned and

35 Fig. 2 a side view, partly in section, of Fig. 1.

In the construction shown the gas passage 3 is arranged within a body 3a resembling a grate bar and provided with gas outlet openings 4 and the upwardly directed air passages 16. The gas 40 outlet openings 4 are covered by lateral rooflike extensions 17 of the body member 3a to prevent fuel from directly contacting with the openings 4. Laterally of the body member 3a the individual 45 grate bars 2 are arranged in the usual manner.

By constructing the gas furnace in the manner

described the installation of special gas pipes as well as their protective covering and the provision of means for lifting them can be dispensed with, as according to the invention all these essential parts of the furnace are combined into 5 a single member having the shape of a grate bar.

I claim:

1. A burner tube for smoke producing devices consisting of an elongated body portion having a chamber extending longitudinally thereof, longitudinal flanges extending laterally from each side of the lower part of the body, said body having a series of longitudinally spaced gas escape openings at each side of the body and leading from said chamber, said flanges being provided 10 with air passages therethrough and positioned to have the air issuing from the passages intersect the gas streams from said openings, and imperforate flanges extending from the sides of the body at the upper part thereof. 20

2. The burner of claim 1 wherein the second mentioned flanges project laterally beyond the first mentioned flanges.

3. The burner of claim 1 wherein the gas escape openings and second mentioned flanges 25 are both inclined downwardly in a direction away from the chamber.

4. The burner of claim 1 wherein the gas escape openings are inclined downwardly and the air openings inclined upwardly in directions away 30 from the central vertical plane of the body.

5. The burner of claim 1 wherein the gas escape openings are inclined downwardly and the air openings inclined upwardly in directions away 35 from the central vertical plane of the body, and the second mentioned flanges are inclined downwardly from said plane and project laterally beyond the first mentioned flanges.

6. The burner of claim 1 wherein the first mentioned flanges extend downwardly at their free 40 edges to form supporting legs having an air channel therebetween from which extends the air openings.

HEINZ BECKER. 45
